UNITED STATES PATENT OFFICE.

THOMAS W. MOORE, OF PLAINFIELD, NEW JERSEY, ASSIGNOR TO THOMAS W. MOORE, JR., OF SAME PLACE.

CAR-PLATFORM.

SPECIFICATION forming part of Letters Patent No. 381,022, dated April 10, 1888.

Application filed January 30, 1888. Serial No. 262,473. (No model.)

To all whom it may concern:

Be it known that I, THOMAS W. MOORE, a citizen of the United States, residing at Plainfield, in the county of Union and State of New Jersey, have invented certain new and useful Improvements in Entrance and Exit Ways for Passenger-Cars; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

The object of my invention is to provide practicable separate entrance and exit ways for elevated and other rapid-transit passenger-cars of city traffic where large numbers of passengers enter and leave through the ends of the cars at frequent stopping-places, so that the present delay of those wishing to enter by having first to wait the leaving of the others through a single passage may be avoided; and it consists of the contrivance for such separate ways without extension of the platforms beyond the present length, which is only long enough for one passage, as hereinafter fully described, reference being made to the accompanying drawings, in which—

Figure 1 is a sectional plan of a portion each of two cars with contrivances illustrating my invention. Fig. 2 is an end elevation of one of the said cars, and Fig. 3 is a sectional elevation of a modified form of the invention.

In the operating of rapid-transit cars of crowded city places there is much confusion on arrival of the cars at the station-platforms by those outside rushing for the only passage-way at the same time those inside are trying to pass out through the same way, causing at many stations much loss of time, during which little or no progress is made by either party, besides the delay which one party must incur by waiting for the other.

To provide for separate entrance and exit ways by making larger platforms is objectionable for various reasons, among which the longer station-platforms that would be necessary, especially for elevated roads, is important, and such remedy would not be available

for cars at present in use. I have therefore contrived for such separate passages with car-platforms of the usual length for one passage by the door *a* in the side of the car next to and inside of the end wall, *b*, through which passengers may find exit, while others may enter through the usual passage, *c*, over the platform; but to avoid making the doorway in the side of the car I will in some cases make the second passage over the end of the platform, *6c*, and an extensible rack which may be provided to compensate for the lack of length at the corners of the platform, due to the curved form necessary for turning short curves by the closely-coupled cars, with a dividing-rail, *l*, to separate the two passages, said rail being bent suitably at *f* and connected with a dividing-post, *g*, located at the middle of the doorway *h* in the end of the car, which will for this purpose be made a little wider than the usual doorway. The rack is in this case made extensible by its main bars *j* being jointed to the middle of the end of the platform at *i*, and having its lateral bars *k* extending into grooves or ways *l* in the platform under the top plate, *75* allowing the corners of the platforms to approach and recede from each other as they vary in turning curves.

The racks extend the whole breadth of the car-platforms for use alike on each side, according as the station-platforms may be, and the confronting racks of the coupled cars will probably sufficiently control each other as to their positions independently of the variations of the platforms by the curves of the road; but they may be coupled together at one or both of their outer corners for this purpose, if desired.

The racks may of course be constructed and arranged in any other approved contrivance suitable for thus extending the platform-corners without interfering with the running of the cars around curves, and the main bars *j* will have any suitable guard-railing, *m*, and suitable gates will be provided for both passages.

The dividing-rail *l* is in this example represented as adapted to turn on its bearing at *n*, so as to be shifted over to the other side when the passages are to be opened that way, the

outer end of said rail being supported on either side in the notched upper end of a post, *o*; but, if desired, said dividing-rail may be made in two parts, each being pivoted in one of said 5 posts at *o*, one to be let down and connected at *n*, while the other is set upright over its supporting-post and retained in any approved way.

It will be seen that with this improvement more than half the time now requisite for *ex-10* change of passengers will be saved, because with the instruction to "keep to the right" once learned and kept in mind by the public both sides may go their way immediately on the stopping of the cars without the obstruc-15 tion of the first attempts of both sides to pass, and also without the waiting of one for the other.

I do not, of course, limit myself as to the length of the car-platforms, as they may be made long 20 enough to have the two passages separated by the dividing-rail without the extensible rack.

I am aware that a single passage having a branch to each side of the car has been proposed; but this only amounts to a single passage 25 to and from whichever side the station-platform may be, and is not practically different from the common arrangement, whereof the single passage turns to right or left over the car-platform, according as the station-30 platform is on one side or the other. My invention is essentially different in that it provides entirely separate and independent si-

multaneous ingress and egress from and to the station-platform, whichever side of the car it may be through which the entering and leaving passengers may pass at the same time, and thus greatly shorten the delay therefor. 35

What I claim, and desire to secure by Letters Patent, is—

1. The improvement in construction of pas- 40 senger-cars which consists of entrance and exit passages separately arranged side by side at the ends of the cars and at each side thereof, substantially as herein shown and described.

2. The improvement in construction of pas- 45 senger-cars which consists of an extensible platform and dividing-rail providing entrance and exit passages side by side over the plat- form, said extensible platform being contractile to allow the turning of the cars on curves, 50 substantially as described.

3. The improvement in construction of pas- 55 senger-cars which consists of separate entrance and exit passages over the platform divided by the guard-rail extending from the middle of the doorway and changeable for dividing the passages to either side of the car, substan- tially as described.

In testimony whereof I affix my signature in presence of two witnesses.

THOMAS W. MOORE.
